SUCKER ROD TIGHTENER

James D. Cavaness, Arlington, Tex.

Application February 26, 1945, Serial No. 579,877

5 Claims. (Cl. 255—14)

1

This invention relates to well pumping apparatus and more particularly to an improved tightener for sucker rods.

An object of this invention is to provide an automatically operable means mounted on and around the polished rod for automatically rotating sucker rods clockwise in one cycle of movement of the rods.

Another object of this invention is to provide a device of this kind which is active on the upward stroke of the polished rod for progressively rotating the rods.

A further object of this invention is to provide a device of this kind which is simple in its construction and positive in its action within certain adjusted load ranges for progressively rotating the sucker rods as the rods are lifted upward.

Further object of this invention is to provide a device of this kind which includes a housing secured about the rod and provided with pawl and ratchet means active under the weight of the lifting of the sucker rods to progressively rotate the same in one direction.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a detail side elevation partly broken away and in section of a polished rod tightening and rotating device constructed according to an embodiment of this invention.

Figure 2 is a vertical sectional view taken substantially on the line 2—2 of Figure 1.

Figure 3 is a sectional view taken on the line 3—3 of Figure 1.

Figure 4 is a fragmentary sectional view taken on the line 4—4 of Figure 1.

Figure 5 is a sectional view taken on the line 5—5 of Figure 2.

Referring to the drawings, the numeral 10 designates an elongated polished rod of conventional construction which is in turn attached to sucker rods extended into a well. A housing generally designated as 11 is disposed about the rod 10 and includes a pair of oppositely extending trunnions 12 which are carried by the opposite end walls 13 and 14. The looped lower ends 15 of a clevis 16 are adapted to engage the trunnions 12, and are connected to the walking beam for raising and

2

lowering the housing 11 to effect vertical reciprocation of the polish rod 10. The housing 11 includes opposite side walls 17 and 18 and a top wall 19. The lower end of the housing 11 is open and is formed with a downwardly tapered or flared flange 19', having a cylindrical flange 20 formed integral therewith, so as to provide a relatively large diameter circular chamber 21 in the lower end of the housing. The top wall 19 of the housing 11 is formed with an opening 22 within which a plate 23 is loosely mounted. The plate 23 has formed integral therewith a bushing 24 which extends partly within the housing 11 and partly above the top wall 19, and is formed with an opening 25 through which the rod 10 loosely engages. The upper end of the bushing 24 is formed with a ball race 26 on which anti-friction balls 27 engage. A second anti-friction element 28 is disposed about the rod 10, being formed with a ball race 29 and a ball retaining ring 30 is interposed between the two races 26 and 29. A split clamp 31 is secured by fastening members 32 to the rod 10 above the anti-friction member 28 and is adapted to hold the rod 10 against lengthwise movement with respect to the anti-friction bearing formed by the bushing 24, the collar 28 and the balls 27.

In order to provide a means whereby the rod 10 will be rotated as the rod is elevated or raised, I have provided at opposite ends of plate 23 a pair of ledges 33, having inclined lower surfaces 34 on which plates 35 are secured by fastening devices 36. A horizontal ledge 37 is carried by each end wall of the housing 11, being formed with a horizontal upper surface 38 on which a bearing plate 39 is secured by fastening devices 40. A wedge 41 is interposed between the two plates 35 and 39 and anti-friction rollers 42 are interposed between the upper inclined side of wedge 41 and plate 35. Anti-friction rollers 43 are interposed between the lower horizontal side 44 of wedge 41 and lower horizontal plate 39.

A rock lever 45 is rockably carried by a pivot 46 and the upper end 47 of rock lever 45 is disposed in a position for engagement with the large end of wedge 41, so that when the wedge moves to the left, as viewed in Figure 4, rock lever 45 will have the lower end thereof shifted to the right. A pivoted pawl or dog 48 is rockably mounted on a pivot 49 engaging through the lower end of rock lever 45 and includes a weighted free end 50. A serrated disc or plate 51 is disposed within the annular flange 20, the teeth 52 of disc 51 being adapted to be engaged by pawl 48. Disc 51 includes a split bushing 53, which is clamped by

means of fastening members 54 to polish rod 10. Disc 51 is held against reverse rotation by a resilient holding dog 55 secured by fastening members 56 to the lower side of flange 19. Holding dog 55 is adapted to engage teeth 52 of plate 51, so that disc or plate 51 will be progressively rotated for rotating rod 10 under the action of the rocking of lever 45. In order to provide for the movement of wedge 41 inwardly with respect to plates 35 and 36 and the idling movement of pawl 48, I have provided a resilient lever operator 57, which is mounted in a housing 58 carried by an obtusely disposed arm 59. A cap 60 telescopes over the housing 58 and confronts the adjacent side of lever 45. Arm 58 is secured to an internally threaded bushing 61, which is threaded onto an elongated tensioning bolt 62, extending downwardly through an opening 63 formed in the top wall 19. Bolt 62 has a collar 64 secured thereabout within the housing 11, so that bolt 62 will be held by cooperation of collar 64 and head 65 against endwise movement, but will be permitted free rotary movement. The vertical position of the resilient member 57 will provide the desired tension on the lower arm of lever 45 for automatically returning wedge 41 to its innermost position.

A vertically disposed flange 66 extends inwardly from an adjacent end wall of the housing and provides an abutment for housing 58, so that this housing will be held against inward movement under pressure of lever 45.

In the use and operation of this device, housing 11 is disposed about rod 10, with disc 51 secured by fastening members 54 to rod 10. Clamp 31 is secured about rod 10 by fastening members 32, bearing against anti-friction member 23. Disc 51 is rotatably retained in flange 20 by means of a split retaining ring 67, engaging in an annular recess 68, carried by flange 20. As rod 10 is raised by upward movement of the walking beam or other elevating means, the weight of rod 10 will through bushing 24, which is movable through opening 22 in top wall 19, cause lateral shifting of wedges 41 to the left, as viewed in Figure 4.

Ledges 33, which are carried by bushing 24 and plate 23, will move inwardly with respect to housing 10 and in this manner effect rocking of the upper end of lever 45 to the left and the lower end thereof to the right. As the lower end of lever 45 rocks to the right, lever tensioning member 57 will be compressed and pawl 48 will rotate disc 51, which is secured to rod 10. As disc 51 rotates holding dog 55 will prevent reverse rotation of disc 51, so that rod 10 will be progressively rotated in one direction during each upward movement thereof.

It will be noted from Figure 2 of the drawings that plate 51 is loosely mounted in flange 20, so that this plate or disc may have sufficient vertical movement within flange 20 to permit relative movement of housing 11 with respect to bearing plate 23. This device will provide for the automatic rotation or tightening of the polished rod, the degree of rotation with each vertical movement of the polished rod being regulated by the length of movement of wedge 41. Wedge 41, with rollers 42 and 43, are held against inward

movement with respect to housing 11 by means of a plate 69 secured by fastening members 70 to ledge 37 and an adjacent end wall.

The upper end 47 of lever 45 is limited in its outward movement by means of an adjusting bolt 71 threaded through housing 11, so that the rocking movement of lever 45 can be regulated to the desired degree.

What is claimed is:

1. A sucker rod tightener comprising a housing engaging about polish rod, oppositely extending trunnions carried by said housing, means engaging said trunnions supporting said housing for vertical reciprocating movement, and means in said housing for effecting rotation of said rod in one direction upon upward movement of said housing, said latter means including a pair of oppositely disposed wedge members slidably mounted in said housing, a plate, movable endwise with respect to said housing and rotatable about said rod, said plate formed with inclined surfaces engageable with said wedge members for sliding said wedge members upon vertical movement of said housing, a pair of rock levers engageable at one end thereof with said wedge members, whereby movement of said wedge members will rock said levers, a pair of oppositely disposed pawls carried by the opposite ends of said levers, and a toothed plate loose in said housing and fixed to said rod, said pawls engaging said plate to thereby effect the rotation of said plate upon rocking of said levers in one direction.

2. A sucker rod as set forth in claim 1 including means for yieldably urging said levers for rocking movement in the opposite direction.

3. A sucker rod as set forth in claim 1 including means for yieldably urging said levers for rocking movement in the opposite direction, wherein the tension of said means urging said levers may be adjusted by a tensioning bolt, accessible exteriorly of said housing.

4. A sucker rod as set forth in claim 1 including a resilient holding dog carried by said housing and engaging with the teeth of said plate, for holding the latter against reverse rotation.

5. A sucker rod tightener comprising a housing engaging about a polish rod, means to vertically reciprocate said housing, means in said housing for effecting rotation of said rod in one direction upon upward movement of said housing, said means including a pair of oppositely disposed wedge members slidably mounted in said housing, correlated means loosely carried by said housing and fixed to said rod for effecting sliding movement of said wedge members upon upward movement of said housing, a pair of rock levers engageable at one end thereof with said wedge members whereby movement of said wedge members will rock said levers, and adjusting means for limiting the rocking movement of said levers, said latter means including a threaded bolt for each lever accessible exteriorly of said housing and interiorly engageable with the upper ends of said rock levers, and means actuated by rocking of said levers in one direction for effecting turning of said rod in one direction.

JAMES D. CAVANESS.
